poration of Illinois

Application March 21, 1932, Serial No. 600,090

6 Claims. (Cl. 68—9)

This invention relates to improvements in ironing machines having relatively movable ironing elements by which clothes are ironed and the purpose of this invention is to provide improved mechanism for actuating one of the ironing elements and effecting relative movement of two ironing elements, such as a rotatable roll and an ironing shoe. The principal object of the invention is to provide improved means for moving the shoe toward and from the roll. A further object of the invention is to provide improved ironing machine mechanism according to which the immediate support for the ironing shoe is slidably mounted for movement toward and from the axis of the roll. A further object of this invention is to provide an ironing machine having motor driven mechanisms for effecting rotation of an ironing roll and for effecting movement toward and from the roll of a slidably mounted ironing shoe. Another object of the invention is to provide improved actuating mechanisms for effecting movement of the shoe toward and from the roll by the operation of a shaft which rotates continuously in the same direction for effecting both movements of the shoe. Other objects of the invention relate to various features of construction and arrangement which will appear more fully hereafter.

The nature of the invention will be understood from the following specification taken with the accompanying drawings in which one embodiment is illustrated.

In the drawings,

Fig. 1 shows a side elevation of the improved ironing machine with parts of the supporting table and its legs broken away;

Fig. 2 shows an enlarged end elevation of the ironing machine, looking toward the right as viewed in Fig. 1, with the cover of the housing removed and other parts shown in vertical section;

Fig. 3 is a detailed section taken on the line 3—3 of Fig. 2;

Fig. 4 shows an enlarged vertical section taken on the line 4—4 of Fig. 2;

Fig. 5 shows a side elevation of the clutch member and cam by means of which the actuation of the shoe is controlled;

Fig. 6 shows an enlarged vertical section on the line 6—6 of Fig. 1;

Fig. 7 shows a vertical section on the line 7—7 of Fig. 6; and

Fig. 8 shows a horizontal section on the line 8—8 of Fig. 6.

As illustrated in the accompanying drawings, the invention is embodied in an ironing machine comprising a supporting table 10 having legs 11, and provided with an opening 10^a in which is located the lower part of a housing 12 provided with flanges 12^a which rest upon the table and

are secured thereto by bolts 13. The housing 12 has a removable cover 14 having formed integrally therewith the casing of an electric motor 15 which is connected to a suitable source of current supply to provide the power for actuating the driving mechanism contained within the housing. The cover plate 14 is detachably secured to the housing 12 by means of cap screws 16 and the cover plate is connected on its inner side by means of bolts 17 with a frame 18 which serves in conjunction with the cover plate and the motor casing to support the driving mechanism actuated by the motor, so that, upon removal of the cap screws 16, the cover plate and the driving mechanism may be removed as a unit from the housing 12. The housing 12 also serves as a support for the ironing roll 19 which is adapted to cooperate with the movable shoe 20, and the mechanism contained within the housing is adapted to effect the rotation of this roll and the movement of the shoe toward and from its ironing position.

The electric motor 15 comprises a field winding 21 and a rotatable armature 22 mounted upon the motor shaft 23 which is journaled at one end in a bearing formed in the motor casing and at the other end in a hub 24 which extends inwardly from the motor casing into the housing. This hub 24 is provided with a bushing 25 in which the shaft 23 is directly journaled and the outer end of the shaft is formed integrally with or has secured thereto a driving pinion 26 arranged to mesh with a gear 27. This gear is secured upon a counter shaft 28 located above the motor shaft 23 and journaled in bearings 29 and 30 which are formed in the upper part of the motor casing and in the frame 18, respectively. This shaft 28 has formed thereon or secured thereto a pinion 31 which meshes with a driving gear 32 of relatively large diameter, mounted to rotate upon the shaft 33 which is journaled at one end in the bearing hub 34 formed integrally with the cover plate 14 and at the other end in a bearing 35 which is formed in the frame 18. This gear 32 is secured to or formed integrally with a pinion 36 which meshes with another gear 37 secured upon the roll driving shaft 38.

The roll driving shaft 38 is journaled in a hub 39 formed in the upper part of the frame 18 and arranged to engage at its ends the circular bore 40 which is formed in the bearing block 41, constructed as an integral part of the housing 12. The shaft 38 is also journaled in a bushing 42 which is secured in this bore 40 and the projecting end of this shaft has secured thereon or formed integrally therewith a driving pinion 43 which is arranged to mesh with a gear 44 secured to the roll 19. This roll is mounted to revolve upon an axle 45 which is secured in stationary

- position in the bearing block 41 by means of a removable pin 46. The roll 19 comprises a sheet metal cylinder 47 which is secured at its ends to radial disks 48, one of which is shown in Fig. 4. 5 This disk extends between the gear 44 and a ring 49 and these parts are secured together by studs 50 so that the roll is driven by the gear which in turn revolves upon a bushing 51 secured upon the axle 45. The outer end of the roll 19 is closed 10 by a plate 53 carried by a hub 54 which revolves upon the outer end of the axle 45 and provision is made at this point for preventing endwise movement of the roll with respect to its bearings on the axle 45. The sheet metal cylinder 47 of 15 the roll is covered by a winding 55 of suitable fabric which is adapted to contact directly with clothes being ironed.
- The pinion 36 which drives the roll 19 also 20 serves to effect movement of the shoe 20 toward and from the roll but, before describing the mechanism which is actuated by the pinion for this purpose, it will be desirable to set forth the means by which the shoe is mounted. As shown particularly in Fig. 6, the shoe 20 comprises a front 25 plate 51, of considerable thickness, which extends substantially throughout the length of the roll and which is curved to conform to the curvature of the roll. This plate 51 has its upper and lower edges reversely bent as shown at 57^a to embrace 30 the backing plate 58 within which is mounted a body of insulating material 59 containing the electric heating element which is connected to a suitable source of current supply so that the shoe may be heated for effecting the ironing of the 35 clothes which are interposed between the shoe and the roll. The shoe 20 is directly supported by a bracket 60 which is secured to the middle point of the backing plate 58 and this bracket 60 is pivotally connected to a pin 61 with the horizontal supporting bar 62 which has a sliding 40 movement toward and from the axis of the roll 19, being preferably arranged to move in a horizontal plane. A leaf spring 63 is secured to the underside of the bar 62 and bears upon the lower edge 45 of the shoe 20, as shown in Fig. 6 so that as the shoe is moved toward the roll, the lower edge of the shoe first engages the roll or the clothes to be ironed which are interposed between the roll and the shoe, and as the movement of the bar 62 continues, the other parts of the shoe are brought 50 into engagement so that it finally assumes a position concentric with the axis of the roll, as shown in Fig. 6. When the shoe is withdrawn from the roll, the extent to which the shoe may 55 be tilted upwardly about the pin 61 by the action of the spring 63 is limited by a pin 64 which projects from the bracket 60 to coact with a lug 65 projecting from the underside of the bar 62.
- The bar 62 which carries the shoe 20 is 60 slidably mounted in a vertically extending pedestal or casing 66 formed in two complementary parts 66^a together with a removable cap 66^b. This casing is provided with flanges 66^c which rest upon the table 10 and are secured thereto by studs 67. 65 The complementary upright portions 66^a of this pedestal or casing are provided with projecting ears 66^d which are secured together by bolts 68. The upper parts of these housing portions 66^a and the cap piece 66^b are similarly provided with 70 projecting ears 66^e which are attached together by bolts 69. The purpose of this sectional construction of the pedestal or casing 66 is primarily to permit the convenient assembly of the parts which are contained therein. The bar 62 is adapted to slide in a guideway 70 formed partly in a

rearward extension 66^f of the casing and a coil spring 71 mounted in this rearward extension of the casing bears against the end of the bar 62 and normally forces it toward the roll 19.

For the purpose of withdrawing the shoe 20 from the roll 19, the supporting bar 62 is provided with an elongated slot 62^a across which extends a transverse pin 74 having mounted thereon a roller 75. This roller is adapted to 10 coat with an inclined cam surface 76^a formed upon a vertically movable plunger 76 arranged to slide in a guideway 77 formed in the pedestal or casing 66. The lower end of this plunger 76 is provided with a circular socket 76^b in which is pivotally mounted the circular terminal portion 15 78^a of an actuating arm 78. This arm is secured at its other end to an eccentric strap 79 mounted to ride upon an eccentric 80 which is fixed upon a rotatable shaft 81. The eccentric strap is formed in two parts secured together by studs 20 82 and these parts are provided with an annular rib adapted to engage a groove 80^a in the eccentric so that the strap is retained against endwise movement. It will be apparent that upon rotation of the eccentric 80 from the position 25 shown in Fig. 6, the arm 78 is forced upwardly, thereby elevating the plunger 76 and causing the cam surface 76^a to retract the bar 62 against depression of the spring 71, thereby withdrawing the shoe 20 from the roll 19. Upon continued 30 rotation of the shaft 81 and the eccentric 80 in the same direction, the plunger 76 is lowered and the coil spring 71 then operates to force the bar 62 inwardly and thereby moves the shoe 20 toward the roll 19.

The shaft 81 is journaled in bearings 83 and 35 84 which are carried by a bracket 85 secured to the underside of the table 10 and the end of this shaft opposite the eccentric 80 is secured through a flexible coupling 86 with an actuating shaft 87. 40 This shaft 87 is journaled in the lower part of an auxiliary housing 88 which is inclined downwardly from the side of the housing 12 through an aperture in the table 10, as shown in Fig. 2. This auxiliary housing is provided at its lower 45 end with a removable cap 88^a and at its upper end it is provided with flanges 88^b which are secured to the housing 12 by studs 89. The shaft 87 has a bevel gear 90 secured thereon within the housing 88 and this beveled gear meshes with another 50 beveled gear 91 secured upon the end of an inclined shaft 92 which is journaled in bearings at the ends of the tubular portion 88^c of the auxiliary housing and which terminates within the casing 12 at a point adjacent to the shaft 33. 55 At this end, the shaft 92 has a beveled gear 93 fixed thereon to mesh with another beveled gear 94 which is fixed upon the shaft 33 so that when the shaft 33 is driven from the pinion 36, the shaft 92 is actuated to operate the connected 60 shafts 81 and 87 and thereby turn the eccentric 80 to control or effect the movement of the shoe toward and from the roll.

The driving connection between the pinion 36 and the shaft 33 is effected through a plurality of 65 clutch teeth 95 which are formed on the side face of the pinion 36 to mesh with corresponding clutch teeth 96 which are formed on the end face of a clutch member 97. This clutch member is splined upon the enlarged portion 33^a of the shaft 70 33 and it is normally forced toward the pinion 36 by means of a coil spring 98 which is mounted upon the tubular extension 97^a of the clutch member to bear at one end against the shoulder on the clutch member and at the other end against 75

the inner face of the cover plate 14. This extension 97^a of the clutch member is mounted to slide upon the hub 34 in which the adjacent end of the shaft 33 is journaled. The clutch member 97 is provided with an annular groove 97^b one side of which has formed thereon a cam surface 99 provided with projections 99^a, as shown particularly in Fig. 5. This groove 97^b is engaged by the end of a shifter bar 100 which extends upwardly and has its upper extremity pivoted on a pin 101 carried by a crank arm 102. This crank arm is fixed upon a shaft 103 and the hub of this arm has an extension 102^a which is journaled in a bearing hub 104 carried by the upper part of the frame 18 as shown in Fig. 4. The shaft 103 is journaled in a hub 105 carried by the cover plate 14 and the projecting end of the shaft has secured thereon a handle 106 which is adapted to be manipulated by the operator of the machine 20 to turn the crank arm 102 and thereby effect longitudinal movement of the shifter bar 100. The lower end of this shifter bar is adapted to slide between an auxiliary plate 107 which is secured to the frame 18 and another plate 108 which is secured to this auxiliary plate by screws 109. The plate 108 has a slot 108^a engaged by a pin 110 secured to the shifter bar so that the longitudinal movement of this bar is limited by the engagement of the pin with the ends of the slot. A coil 30 spring 111 is connected between the pin 101 and one of these screws 109 so that it tends normally to move the shifter bar 100 downwardly and maintain the extremity thereof in engagement with the clutch member 97. The clutch member 35 is provided on opposite sides of the groove 97^b with two recesses 97^c which are adapted to be engaged by the end of the shifter bar under the influence of the spring 111 thus holding the clutch member in either of two positions, corresponding 40 to the rotation of the shaft 33 through 180°. When the shaft 33 is in one of these positions, the shoe 20 is in a position fully withdrawn from the roll 19 and when the shaft 33 is in the other position, 180° therefrom, the shoe is in its innermost position adapted to engage and iron the clothes which are passing around the roll 19.

Assuming that the clutch member 97 is disengaged from the pinion 36, as shown in Fig. 4, the actuation of the handle 106 to withdraw the shifter bar 100 from engagement with a recess 97^c in the clutch member, will then cause the clutch member to be moved inwardly under the influence of the spring 98 until the clutch teeth 96 on the clutch member engage the clutch teeth 55 95 on the pinion, whereupon the clutch member is driven by the pinion to rotate the shaft 33 and thereby, through the connected parts, actuate the eccentric 80 and cause the shoe 20 to be moved with respect to the roll. Assuming that the shoe 60 is then moved toward the roll, the movement continues while the eccentric 80 rotates through one hundred and eighty degrees when the shoe will be found to be in ironing position in which position it is held by the action of the shifter bar 65 100 in disengaging the clutch member 97 and entering one of the recesses 97^c to hold the clutch member and the shaft 33 against rotation. The shoe then remains in ironing position until the operator again withdraws the shifter bar 100 by 70 turning the handle 106, and then the clutch again engages the pinion and drives the shafts 33 and 81, in the same directions as before, until the shoe is in its fully retracted position, when the shifter bar disengages the clutch and engages the 75 other recess 97^c to hold the shoe in that position.

Although one form of the invention has been shown and described by way of illustration, it will be understood that it may be constructed in various other forms coming within the scope of the appended claims.

We claim:

1. The combination in an ironing machine, of a table, a housing carried by said table, an ironing roll carried by said housing and projecting over said table, an ironing shoe extending alongside said roll, a casing mounted on said table between the ends of said roll, a member slidably mounted in said casing and supporting said shoe, driving mechanism in said housing for rotating said roll, a shaft extending from said driving mechanism in said housing parallel to said roll, and means actuated by said shaft within said casing for moving said member and said shoe.

2. The combination in an ironing machine, of an ironing roll, an ironing shoe, a slidably mounted member supporting said shoe, a plunger having an inclined surface adapted to effect the movement of said slidably mounted member, and a rotatable cam operatively connected with said plunger for effecting movement of said plunger.

3. The combination in an ironing machine, of a housing, means for supporting said housing, an ironing roll carried by said housing and extending endwise therefrom, an ironing shoe extending alongside said roll, a slidably mounted member located between the ends of said shoe for supporting said shoe, a shaft extending from said housing parallel to the axis of said roll, means operated by said shaft for actuating said slidably mounted member to move said shoe with respect to said roll, and driving mechanism in said housing for rotating said roll and rotating said shaft.

4. The combination in an ironing machine, of a housing, a rotatable ironing roll extending endwise from said housing, a shoe extending alongside said roll, a supporting member mounted midway between the ends of said shoe, a slidably mounted member movable horizontally in said supporting member and having said shoe mounted thereon, a vertically movable plunger for actuating said slidably mounted member, a shaft extending from said housing beneath said roll and having connections for operating said plunger, and driving mechanism within said housing for rotating said roll and actuating said shaft.

5. The combination in an ironing machine, of a rotatable roll, a shoe extending parallel to said roll, a slidably mounted member movable in a horizontal plane toward and from said roll, said shoe being mounted on said slidably mounted member, a roller carried by said member, a vertically slideable plunger having an inclined surface to coat with said roller, and power driven means for actuating said plunger.

6. The combination in an ironing machine, of a rotatable roll, a shoe extending parallel to said roll, a slidably mounted member movable in a horizontal plane toward and from said roll, said shoe being mounted on said slidably mounted member, a roller carried by said member, a vertically slideable plunger having an inclined surface to coat with said roller, a rotatable shaft, an eccentric fixed on said shaft, and an eccentric strap surrounding said eccentric and having connection with said plunger for effecting reciprocation of said plunger upon rotation of said shaft.
